UNITED STATES PATENT OFFICE

2,383,305

TOY

Joseph Greene, Brooklyn, N. Y., assignor to Holgate Brothers Company, Kane, Pa., a corporation of Pennsylvania

Application December 18, 1943, Serial No. 514,833

10 Claims.

(Cl. 46—177)

This invention relates to toys and more particularly to an educational toy designed to effect hand and eye coordination, to teach color discrimination and recognition of the musical scale.

One of the objects of the invention is to provide a toy requiring the exercise of skill in elevating a ball to a point where it will be introduced into a runway that will return it to its lowest position.

Another object is to supply such a toy in which the ball runway may be combined with musical elements to simulate the scale, and, also, with means for effecting the movement of animated objects.

With the foregoing objects outlined and with other objects in view, which will appear as the description proceeds, the invention consists in the novel features hereinafter described in detail, illustrated in the accompanying drawings, and more particularly pointed out in the appended claims.

Referring to the drawings:

Fig. 1 is a front elevation of my novel toy.

Fig. 2 is a vertical sectional view on the line 2—2 of Fig. 1.

Fig. 3 is a horizontal sectional view of a detail.

Fig. 4 is a vertical sectional view of such detail taken on the line 4—4 of Fig. 3.

In the drawings, 10 designates a case consisting of a base 11, side walls 12, rear wall 13, and a top 14.

The front of the case may either be open or closed by a transparent wall.

Resting on the base is a vertically disposed strip 15 provided with an upper edge 16 serving as a fulcrum for finger-operated keys 17. These keys simulate piano keys and each may be provided at its bottom with a transverse notch 18 to receive the upper edge of the strip 15.

Immediately above the keys, a front board 19 extends across the casing and has its ends secured to the sides thereof, and extending rearwardly from the upper edge portion of the board is a substantially horizontal guide strip 20.

An internal wall 21 is arranged in the case between the rear wall 13 and the rear edge of the strip 20 and may be provided with decorative figures 22.

Between the parts 20 and 21 and guided thereby is a series of posts 23 that are gradually increased in height from one end of the case to the other. Each of the posts is provided with a horizontal notch 24 to receive the rear end of a key 17 and when the key is depressed, the post with which

it is associated will be elevated to a height equal to the next higher post.

The tops of all of the posts are inclined toward the partition 21 and all of them with the exception of the tallest one are inclined toward the tallest one, and, therefore, if a marble or ball 25 is placed on the lowermost one, it can be gradually elevated by the posts to the tallest one of the series by successive manipulation of the keys. 10 When a key is depressed, the marble will be elevated to a level where it can roll to the next higher post and so on.

As the top of the tallest post is inclined toward the internal wall 21, the marble when elevated by the tallest post, can roll therefrom into the entrance 26 of a runway 27. The runway is inclined from the entrance toward an exit 28 which will discharge the marble onto the lowest one of the posts. The entrance and exit are preferably arranged in the internal wall 21 and the runway is positioned between such wall and the rear wall 13.

As the marble rolls down the runway, it can be used for the creation of musical sounds. For example, metal plates 29 having different musical tones may be positioned along the bottom of the runway so that the marble will strike each one in descending therethrough. Such plates may give out the sounds of the musical scale.

In addition, the marble in rolling through the runway, may rotate a disk 30 mounted on a horizontal shaft 31. If this feature is used, a window 32 in the internal wall 21 may be employed to exhibit figures 33 on the disk. For example, the front of the internal wall may be decorated to illustrate the Mother Goose rhyme "The cow jumped over the moon." In that event, the moon figure would be arranged beneath the window 32 and the front of the disk could be provided with the figure of a cow which would be periodically displayed in the window as the keys are operated.

As minor details, a bumper 34 may be arranged on one of the side walls at the lower end of the runway to cushion the marble, and immediately forward of the shorter one of the posts a guide strip 35 may be secured to one of the side walls to prevent the falling marble from dropping off the shortest one of the posts. It will be obvious that more than one marble may be used at the same time and may be progressively elevated by the depression of the keys.

I wish it distinctly understood that the toy described and illustrated is simply an example of what should be embodied therein, and it is manifest that changes and variations may be made

as may be convenient and desirable without departing from the salient features thereof. I, therefore, intend the following claims to cover such modifications as naturally fall within the lines in the invention.

What I claim and desire to secure by Letters Patent is:

1. A toy of the character described comprising a wall having an entrance opening and an exit opening therein, a ball runway communicating with said openings and inclined downwardly from the entrance opening to the exit opening, musical creating means defining a portion of said runway and arranged to be actuated by said ball as it travels down the runway, said runway being arranged at one side of said wall, and manually operated means arranged at the opposite side of the wall and comprising successively actuated posts, movable relatively to one another, for progressively elevating a ball from the exit opening to the entrance opening and for discharging the ball into the latter.

2. A toy of the character described comprising a wall provided with an entrance opening, an exit opening, and a window, a ball runway arranged at one side of said wall and inclined downwardly from the entrance opening to the exit opening, movable means to display objects through said window, projecting into the runway, and adapted to be actuated by a ball rolling through the runway, and manually operated means arranged parallel to and at the opposite side of said wall and comprising successively actuated posts, movable relatively to one another, for progressively elevating a ball from the exit opening to the entrance opening and to cause the ball to roll into the latter opening.

3. A toy of the character described comprising a wall provided with an entrance opening, an exit opening, and a window, a ball runway arranged at one side of said wall and inclined downwardly from the entrance opening to the exit opening, movable means to display objects through said window, projecting into the runway, and adapted to be actuated by a ball rolling through the runway, and manually operated means arranged parallel to and at the opposite side of said wall for progressively elevating a ball from the exit opening to the entrance opening to cause the ball to roll into the latter opening, the last-mentioned means comprising a series of relatively reciprocatable posts of gradually increasing height from the exit opening to the entrance opening, and a finger operated key for raising each post.

4. A toy of the character described comprising a wall provided with an upper entrance opening and a lower exit opening, a ball runway arranged at one side of said wall, parallel thereto and inclined downwardly from the entrance opening to the exit opening, a series of relatively reciprocatable posts arranged parallel to the wall at the opposite side thereof, said posts gradually increasing in height from the shortest one of the series to the tallest one of the series, the shortest one of the series being positioned to receive a ball discharged from said exit opening and the tallest one of the posts being adapted to project a ball into said entrance opening, the posts which are shorter than the tallest one having surfaces inclined toward the tallest post so that a ball can roll from a shorter post to the next higher one when the shorter post is elevated a sufficient height, and a series of substantially horizontal rockable keys projecting away from said wall and operatively connected to said posts for successively

elevating the latter independently of one another.

5. A toy of the character described comprising a wall provided with an upper entrance opening and a lower exit opening, a ball runway arranged at one side of said wall, parallel thereto and inclined downwardly from the entrance opening to the exit opening, a series of relatively reciprocatable posts arranged parallel to the wall at the opposite side thereof, said posts gradually increasing in height from the shortest one of the series to the tallest one of the series, the shortest one of the series being positioned to receive a ball discharged from said exit opening and the tallest one of the posts being adapted to project a ball into said entrance opening, the posts which are shorter than the tallest one having surfaces inclined toward the tallest post so that a ball can roll from a shorter post to the next higher one when the shorter post is elevated a sufficient height, and a series of substantially horizontal rockable keys projecting away from said wall and operatively connected to said posts for successively elevating the latter independently of one another, said posts being visible to a person actuating the keys.

6. A toy of the character described comprising a substantially vertical wall, a series of relatively reciprocable posts arranged parallel to the wall immediately in front thereof, said posts being positioned side by side in close proximity to one another and gradually increasing in height from the shortest to the tallest post of the series, the posts which are shorter than the tallest one having ball supporting surfaces inclined toward the tallest post so that a ball can roll from a shorter post to the next higher post when the shorter post is elevated to a sufficient height, a ball runway having an entrance to receive a ball from the supporting surface of the tallest post and an exit to discharge a ball onto the supporting surface of the shortest post, and manually operated means for successively raising the posts independently of one another.

7. A toy of the character described comprising a substantially vertical wall, a series of relatively reciprocable posts arranged parallel to the wall immediately in front thereof, said posts being positioned side by side in close proximity to one another and gradually increasing in height from the shortest to the tallest post of the series, the posts which are shorter than the tallest one having ball supporting surfaces inclined toward the tallest post so that a ball can roll from a shorter post to the next higher post when the shorter post is elevated to a sufficient height, a ball runway having an entrance to receive a ball from the supporting surface of the tallest post and an exit to discharge a ball onto the supporting surface of the shortest post, the portion of the toy immediately in front of said supporting surfaces of the posts being unobstructed so that the ball if not manipulated properly can fall forward from the supporting surface of any of the posts, and manually operated means for successively raising the posts independently of one another.

8. A toy of the character described comprising a substantially vertical wall, a series of relatively reciprocable posts arranged parallel to the wall immediately in front thereof, said posts being positioned side by side in close proximity to one another and gradually increasing in height from the shortest to the tallest post of the series, the posts which are shorter than the tallest one having ball supporting surfaces inclined toward the tallest post so that a ball can roll from a shorter post to the next higher post when the shorter post

is elevated to a sufficient height, a ball runway having an entrance to receive a ball from the supporting surface of the tallest post and an exit to discharge a ball onto the supporting surface of the shortest post, and finger operated keys operatively connected to the posts for successively raising them independently of one another.

9. A toy of the character described comprising a series of substantially vertical relatively reciprocable posts positioned side by side in close proximity to one another and having ball supporting surfaces at gradually increasing elevations from one end of the series toward the other end of the series, the supporting surfaces of all of the posts with the exception of the one having the highest supporting surface being inclined toward the last mentioned post so that a ball can roll from the supporting surface of one post to the next one having a higher elevation when a post is moved to a predetermined height, a ball runway having an entrance to receive a ball from the supporting surface at the highest elevation and an exit to discharge the ball onto the

supporting surface at the lowest elevation, and manually operated means for successively raising the posts independently of one another.

10. A toy of the character described comprising a substantially vertical wall, a series of relatively reciprocable posts arranged parallel to the wall immediately in front thereof, said posts being positioned side by side in close proximity to one another and gradually increasing in height from the shortest to the tallest post of the series, the posts which are shorter than the tallest one having ball supporting surfaces inclined toward the tallest post so that a ball can roll from a shorter post to the next higher post when the shorter post is elevated to a sufficient height, a ball runway at the rear of the wall having an entrance in the wall adjacent to the top of the tallest post and an exit in the wall adjacent to the top of the shortest post, and finger operated keys operatively connected to the posts for successively raising them independently of one another.

JOSEPH GREENE.
